Attorney.

UNITED STATES PATENT OFFICE.

RUSSELL HART, OF LOS ANGELES, CALIFORNIA.

PHOTO-ELECTRIC MEANS FOR REPRODUCING SOUND FROM GRAPHICAL RECORDS.

Application filed November 1, 1924. Serial No. 747,313.

To all whom it may concern:

Be it known that I, RUSSELL HART, a citizen of the United States, residing at Los Angeles, in the county of Los Angeles and State of California, have invented a new and useful Photo-Electric Means for Reproducing Sound from Graphical Records, of which a specification is set forth below.

10 In this specification, and the accompanying drawing, I shall describe and show a preferred form of my invention, and specifically mention certain of its more important objects. I do not limit myself to the 15 forms disclosed, since various changes and adaptations may be made therein without departing from the essence of my invention as hereinafter claimed; and objects and advantages, other than those specifically mentioned, 20 are included within its scope.

My invention relates to photo-electric means for reproducing sound from graphical sound records. In a general way its object is to improve the quality or fineness 25 of sound reproduction so that, if the record truly represents the original sound in quality, the reproduction will be true in quality also.

More specifically my principal objects 30 are; first, to provide sound reproducing means adapted to respond to exceedingly small variations in graphical sound records; second, to furnish facilities for obtaining the full effect of the recorded overtones in 35 the reproduction so that the quality of the reproduced sound will correspond very closely to the original; third, to obviate the effect of "stray noises" in the reproduction due to mechanical vibrations; and, fourth, 40 to secure the above results by means of apparatus of great simplicity and relatively low cost.

My invention is particularly adapted for the reproduction of sound from photographic film records, but may be used also for reproducing from other graphical sound records. I prefer to use a photographic film record of substantially constant density and variable width, but a film having a 45 record thereon of uniform width and varying density may be used with practically equal facility.

The objects of the invention are attained in the manner illustrated in the accompanying drawing, in which—

Figure 1 is a diagram showing a typical

arrangement of my apparatus for reproducing sound from a photographic film record;

Figure 2 is a front elevation of a portion 60 of a photographic film with a sound record thereon; and a "gate" through which it is made to slide, and by which it is definitely positioned;

Figure 3 is a longitudinal section of the 65 above gate and film; and a side elevation of a preferred type of photo-electric cell attached to the gate at the rear;

Figure 4 is a rear sectional elevation of 70 the above cell;

Figure 5 is a side elevation of a preferred type of incandescent lamp I use as a primary light source in my apparatus; and

Figure 6 is a diagram, greatly enlarged 75 and exaggerated, to illustrate the manner in which reflection of the light from the primary source may be utilized for obtaining a much attenuated image thereof for use as a secondary source which is directly employed for the reproduction of sound. 80

Similar reference numerals refer to similar parts throughout the several views.

In apparatus of this general character, wherein a luminous rectilinear filament is employed as a source of light, it has hitherto been the effort to make use of a very tenuous filament in order to have the reproduction as free as possible from the effects of "blurring" inevitably accompanying the use of a wide band of light. I have found 85 that the light emanating from tenuous incandescent filaments is very far from constant as the result of unavoidable vibration, and that this causes a distortion of the reproduced sound quite as objectionable as the 90 blurring. It is believed that the changes in light emanation in such filaments, when subjected to vibration, is due to changes in the electrical conductivity resulting from 95 variations in tension caused by the vibration; and I have found that relatively stout filaments do not give this trouble.

In my apparatus, therefore, I employ for the primary light source an incandescent lamp 7 having a relatively thick and strong 100 rectilinear filament 8, not appreciably affected in light emanation by mechanical vibrations. I mount this lamp adjustably on a stand 9, which also adjustably supports a small cylindrical mirror 10 serving as a 105 secondary light source for the reproduction of sound.

It is well known that an object reflected from a cylindrical mirror appears to be greatly attenuated in the direction of the axis of the mirror, and that this effect becomes more marked as the radius of the cylindrical surface is decreased. This effect is diagrammatically illustrated in Figure 6 wherein, to the observer's eye at 11, the image of filament 8 appears very much thinner than the filament. The apparent width of the image is the distance between the rays at 12. By the utilization of this principle it is possible to employ a stout incandescent filament, not appreciably affected by vibration, and make direct use of its greatly attenuated reflected image. An exceedingly thin band of light, having a great intrinsic brilliancy thus becomes available for sound reproduction by photo-electric means.

As illustrated, the sound record 13 consists of a photo-exposed and developed area of substantially uniform density and very much varying width, appearing as a relatively narrow longitudinal band parallel to, and near one edge of, a motion picture film 14. It is usually preferable to have the outer edge 15 of this record rectilinear, and this edge may then be considered to represent the axis of abscissae of a very irregular curve 13 corresponding to the recorded sound wave. The ordinates of the curve represent volume of sound, or loudness, and the distance between peaks, or corresponding points on the curve, correspond to pitch. The overtones and fundamentals of the recorded sound determine the shape of curve 13.

In prior applications for United States patents (No. 608,499 filed Dec. 22, 1922 and No. 630,870 filed April 9, 1923) I have shown and described means for producing such sound records as above described upon uniformly moving photographic films. The recording process therefore need not be described herein.

For reproducing purposes the type of photographic film record described, or a similarly produced type having a record of uniform width and varying density, is made to travel at the recording speed through a "gate" 16. This may be accomplished by driving the film sprocket 17 by means of a motor 18, the film being unwound from reel 19 and re-wound upon reel 20. Figure 1, being diagrammatic rather than pictorial, does not illustrate the mechanism by which reel 20 is driven to accomplish the re-winding. Such means, however, are well known to those familiar with the motion picture and allied arts.

The approved form of sound gate illustrated comprises a fixed plate 21, having a hinged cover 22, and two pairs of polished raised runners 23 and 24 between which the

film runs. One pair of these runners is shown in side elevation in Figure 3, and the position of the two pairs, relative to the film, is shown in dotted lines 25 in Figure 2. Runners 23 are fixed or made integral with plate 21, and runners 24 are pressed inwardly from cover 22 by springs 26 guided by studs 27.

Cover plate 22 is provided with a small rectangular aperture 28, and there is a similar aperture 29 in the rear plate of the gate. Behind the latter aperture is mounted a suitable, highly sensitive, photo-electric cell 30.

The type of photo-cell here shown comprises a very fine platinum grid 31 filled with selenium or other photo-active material, on a glass or quartz cover plate 32, and connected by platinized strips 33 to terminal wires 34. A cup 35 containing anhydrous calcium chloride is sealed upon the cover plate enclosing the photo-active material and grid.

A process for making an exceedingly sensitive and rapid photo-electric cell of the above described type has been fully described in United States Patent No. 1,491,040, issued to me on April 22, 1924.

In operation my reproducing apparatus is assembled in the manner indicated in Figure 1 with a lens system 36 intermediate cylindrical mirror 10 and gate 16. By means of these lenses a sharp secondary image of the mirrored image of the luminous filament is focused upon the sound record of the film. This brightly illuminates an exceedingly narrow transverse band of the record, and the light rays that pass through the film are variably modulated thereby and impinge upon the photo-electric grid 31. This constantly varying light flux will proportionately vary the electrical resistance of the photo-active material in the grid, and thus make it possible to reproduce the original sound by telephonic means.

There are various well known means for amplifying a small electric current, modulated by the action of a photo-electric cell, to make it available for operating loud-speaking devices. One method of doing this is illustrated diagrammatically in Figure 1, wherein certain standard electrical devices are conventionally shown. In this diagram a loud-speaking instrument is indicated at 37, an audion at 38, a variable ratio transformer at 39, a variable resistance at 40, and a condenser at 41. The diagram shows a satisfactory manner for connecting these devices to batteries 42 and 43, with the photo-electric cell 30 in circuit in the system.

The use of quartz for plate 32, upon which the photo-active material of the cell is deposited, is desirable on account of the optical qualities of this substance, and also because

its coefficient of expansion is very small or negligible.

I desire to emphasize the point that variation of light flux from the source of illumination, due to mechanical vibration, may be eliminated in the above described manner. Also that, by reason of the exceedingly thin band of light falling upon the film, there is practically no blurring of the reproduced sound due to overlapping of the effects of adjacent portions of the sound record.

Having thus fully described my invention, I claim:

15 1. Photo-electric sound reproducing means comprising; a movable optical film with a sound record thereon adapted for variably intercepting light rays; a linear light source; and a cylindrical mirror whereby an attenuated image of said source may be thrown upon said record.

20 2. Photo-electric sound reproducing means comprising; a movable optical film with a sound record thereon adapted for variably intercepting light rays; a linear light source; a cylindrical mirror whereby an attenuated image of said source may be thrown upon said record; and a photo-electric cell behind the record adapted for modulating an electric current by the rays transmitted by said record.

25 3. Photo-electric sound reproducing means comprising; a movable optical film with a sound record thereon adapted for variably

intercepting light rays; a linear light 35 source; a cylindrical mirror adapted for reflecting an attenuated image of said source; and a lens intermediate said mirror and said record whereby reflected light rays from the former may be focused upon the latter.

40 4. Photo-electric sound reproducing means comprising; a movable optical film with a sound record thereon adapted for variably intercepting light rays; a linear light source; a cylindrical mirror adapted for reflecting an attenuated image of said source; a lens intermediate said mirror and said record whereby reflected light rays from the former may be focused upon the latter; and a photo-electric cell behind the record adapted for modulating an electric current by the rays transmitted by said record.

45 5. Photo-electric sound reproducing means comprising the elements set forth in claim 4 in combination with; means for passing an electric current through said cell for modulation thereby; and means for utilizing said modulated current for the reproduction of sound.

50 6. Photo-electric sound reproducing means comprising the elements set forth in claim 4 in combination with; means for passing an electric current through said cell for modulation thereby; and means for amplifying and telephonically utilizing said modulated current for the reproduction of sound.

RUSSELL HART.
